UNITED STATES PATENT OFFICE.

ARTHUR GROVER FITZ GERALD, OF BROOKLINE, MASSACHUSETTS.

FLAG SUPPORT FOR AUTOMOBILES.

1,413,267.

Specification of Letters Patent. Patented Apr. 18, 1922.

Application filed October 19, 1920. Serial No. 418,088.

To all whom it may concern:

Be it known that I, ARTHUR GROVER FITZ GERALD, a citizen of the United States, and a resident of Brookline, county of Norfolk, 5 State of Massachusetts, have invented an Improvement in a Flag Support for Automobiles, of which the following is a specification.

This invention relates to supports for pennants and small flags on automobiles and has for its object to provide a form of support which may be readily applied to any ordinary form of automobile, and may be readily removed therefrom, and which, when 15 in use, will hold the front end of the pennant tightly stretched.

Also to provide a support which is of simple construction, and may be produced and applied at small expense.

20 I accomplish these objects by the means shown in the accompanying drawing, in which:

Fig. 1 is a side elevation illustrating an embodiment of my invention.

25 Fig. 2 is a view, on an enlarged scale, showing the support detached from the automobile.

Fig. 3 is a section view at line 3—3 of Fig. 1.

30 Figs. 4, 5, 6 and 7 are detail views showing a modification, Fig. 5 being a section on line 5—5 of Fig. 4.

According to my invention, I provide a resilient, flag-supporting arm *a*, which is 35 preferably formed from a thin, flat strip of spring steel, which, when located in the position hereinafter described, will be almost invisible. Said arm is connected, at one end, to the mud-guard *b* of an automobile, at a point directly over the middle of 40 the front wheel, which is usually the highest point in the guard, and from which point the guard slopes downward, as it extends rearward.

45 Said arm is connected to the guard in a manner to permit ready removal and detachment, a preferred method, as shown in Figs. 1 and 2, being to form an aperture *b*¹ in the guard, at the point above indicated, and 50 form a right angularly bent toe *a*¹ on the end of the arm, which is adapted to be inserted therein, shoulders *a*² being formed at each side of said toe for engagement with the upper surface of the guard.

55 In placing the arm in position, it is held nearly vertically, when the toe is inserted,

and then it is swung rearwardly to an oblique position, so that the toe portion will engage the under side of the mud-guard and the shoulders *a*² will bear on the upper side 60 thereof, thereby supporting the arm in an oblique position. An eye *a*³ is formed in the opposite end of the arm *a* from the support end, and, when the arm is formed of flat material, as shown, the end portion, in 65 which the eye *a*³ is formed, is twisted so that the end portion will be in vertical position, when the arm is in position for use.

Two small apertures *c* are formed, side by side, in the mud-guard at a point directly 70 beneath the aperture *a*³ of the arm, when in position, said apertures *c* being adapted and arranged to receive one end of an S-hook *d*. An S-hook *e* is also arranged in the aperture *a*³, and the flag or pennant *f* is attached to 75 said hooks, as shown in Fig. 3, by inserting them in the grommets located in the corners thereof. Any other convenient means of attachment may be employed. The normal position of the arm is indicated by the 80 dotted line position of Fig. 1, so that it must be placed under tension to permit the attachment of the flag, so that, when attached, the arm will hold the front edge of the flag taut, as shown in Fig. 1.

It will be apparent that the flag and arm may be readily removed by merely detaching the hook *d* from the guard and then removing the arm from the aperture in which it was placed.

In Figs. 4 to 7 a modified form of means for attaching the arm to the mud-guard, is shown, said means consisting of an apertured clip *g*, which is secured to the top portion of the mud-guard and is provided with 90 lugs *g*; beneath which the end portion of an arm *h*, similar to arm *a*, is adapted to be inserted. To hold the arm in position in the clip, the arm is provided with a spring tongue in the middle of its end portion, said 95 tongue having a curved middle portion, which is adapted to engage in a corresponding recess *g*² in the clip, so that, when the arm is inserted beneath the lugs, the tongue will spring into said recess and lock the 100 arm in position, as shown in Fig. 4.

In lieu of the aperture *c*, for attaching the hook *d* to the mud-guard, an eye *h* may be permanently secured to the guard, as indicated in Fig. 7.

With either form illustrated, the flag and arm may be readily attached or detached

and, when in position of use, will not rattle from the vibrations of the mud-guard.

- In practice the relative length of the arm, the width of the pennant, and the rearward 5 inclination of the mud-guard, will be such that the arm will be drawn down nearly to a horizontal position, so that the greater portion of the pennant will be below the level of the highest portion of the guard. 10 The arm will also be in such a position that it will have the hood of the automobile as a background, which tends to decrease its visibility.

I claim:

- 15 1. A flag support for automobiles comprising a resilient arm and means for detachably connecting the same, at one end, to the automobile, means at the opposite end of said arm adapted for connection to one 20 corner of the flag and means for connecting

the opposite corner of the flag to the automobile in position to permit the front edge of the flag to be held under tension by the resilient action of the arm.

2. In combination with the mud-guard of 25 an automobile, a resilient arm, a socket on the guard, at a high point thereof, adapted to receive one end portion of said arm, and to hold the same in a position to extend rearward, means at the opposite end of said arm 30 adapted for connection to the flag and means on a lower portion of the guard and beneath the last named end of the arm, to connect the opposite corner of the flag thereto and hold the flag against the resilient action of 35 the arm.

In testimony whereof, I have signed my name to this specification.

ARTHUR GROVER FITZ GERALD.
